UNITED STATES PATENT OFFICE.

JAMES M. RIHN AND WILLIAM RIHN, OF LOUISVILLE, KENTUCKY.

CONTINUOUS-RAIL CROSSING.

1,378,277.

Specification of Letters Patent.

Patented May 17, 1921.

Application filed March 5, 1921. Serial No. 449,816.

To all whom it may concern:

Be it known that we, JAMES M. RIHN and WILLIAM RIHN, citizens of the United States of America, residing at Louisville, in the 5 county of Jefferson and State of Kentucky, have invented certain new and useful Improvements in Continuous-Rail Crossings, of which the following is a specification.

This invention relates to railroad crossings and has special reference to what is termed a continuous rail crossing.

The principal object of the present invention is to improve and simplify the general construction of devices of this character.

15 A second object of the invention is to provide an improved device which is capable of being applied to any existing railroad crossing to form the same into a continuous rail crossing.

20 A third object of the invention is to provide an improved form of such device wherein the operation will at all times be positive.

A fourth object of the invention is to provide a device of this character of improved 25 construction which may be connected by simple means to a railroad gate or the like so that it may be used for the intersections of street and steam railways and other like places.

30 With the above and other objects in view, as will be hereinafter apparent, the invention consists in general of certain novel details of construction and combinations of parts hereinafter fully described, illustrated 35 in the accompanying drawings, and specifically claimed.

In the accompanying drawings, like characters of reference indicate like parts in the several views, and:—

40 Figure 1 is a perspective view of a railroad crossing constructed in accordance with this invention.

Fig. 2 is a section through one of the rails looking toward the crossing and showing the 45 exterior of the appliance in elevation.

Fig. 3 is a plan view of the intersection at one corner of the crossing.

Fig. 4 is a section on the line 4—4 of Fig. 3.

50 Fig. 5 is a section on the line 5—5 of Fig. 3.

Fig. 6 is a section on the line 6—6 of Fig. 4.

Fig. 7 is a detail perspective of one of the 55 plug retaining plates or blocks.

Fig. 8 is a similar view of the other block.

Fig. 9 is a detail perspective of one of the filler blocks or plugs used herewith.

Fig. 10 is a detail perspective of the other 60 filler member or plug.

Fig. 11 is a detail perspective of a double cam wedge used herewith.

In carrying out the objects of the invention in the form herein described there is 65 provided at each corner of the crossing a casing 10 having a bottom 11. From this casing on all four sides project lugs 12 whereto the rails R may be secured by means of bolts 13.

It is to be noted that the lugs 12 are so positioned as to bring the rails just 70 to the top of the casing. The sides of this casing are slotted as at 14, the outer sides of

said slots being alined with the inner sides of the rails R so that provision is made for the passage from one rail section to the other 75

of the wheels, said slots accommodating the wheel flanges. Held within the casing by 80 bolts 15 are blocks 16 each formed in two parts for convenience in assembling the various parts of the device. These blocks 16

are provided with vertically disposed recesses 17 having enlarged portions 18 at the bottom. Slidable vertically in the recesses 17 are filler members 19 which are of general 85

inverted T-shape, the heads being shown at 20 and each head being beveled as at 21. Slidable on the bottoms of the recesses 18 is 90 a double cam wedge 22. The filler members 19 are arranged with their cam or wedge faces 21 in opposite directions and the cam wedge 22 is so located that moving this cam wedge in one direction forces one part of the wedge beneath one of said filler members and moves the other part of the wedge from beneath the other filler member. Movement 95

in the opposite direction will, conversely, permit lowering of the first member and raising of the second. In addition to the vertical recesses 17 which in one of the members 16 extends clear across said member 100 to form a slot in alinement with two of the slots 14 there is also provided in the other filler member a slot 23 which alines with the slot just mentioned. Furthermore the block having the slot 23 is rabbeted as at 24 to provide a longitudinal slot alined with the other pair of slots 14. The filler members 19 and the cam wedge 22 are so proportioned that with the cam wedge beneath one of the filler members the top of that member will be 110 raised to the top of the slot thus making a continuous rail as can be clearly seen in Fig.

3. Of course when this particular member 19 is depressed the other member will be raised to form a continuation of the remaining rail sections. It is to be noted that the recesses 17 are disposed on the outer sides of the intersecting slots so that when the filler members 19 are raised these filler members form rail continuations.

10 Adjacent each of the recesses 18 is a pocket 25 wherein is pivoted a bell crank lever 26 one arm of which engages on top of the T head of the respective filler member 19. The other arm of this bell crank lever 26 drops behind the square end of the portion of the cam wedge which controls the respective filler member. With this construction when the cam wedge is withdrawn from beneath the filler member the bell crank is positively rotated and positively 20 forces said filler member downward.

Supported in suitable bearings 27 is a rock shaft 28 provided with a rock arm 29 hereby connected by a rod 30 with any suitable operating device as, for instance, a railroad gate. On the rock shaft 28 are also double rock arms 31 and to each arm of each double rock arm is connected a rod 32 which passes through a suitable opening 33 in one of the filler members and is connected within the recess 18 to the cam wedge 22 whereby to operate the same. From this construction it will be seen that rocking the shaft 28 in one direction will force all of the wedges 22 toward the rock shaft 28 and thus simultaneously raise the filler blocks for filling the gaps over which train wheels must pass when driven on one pair of the tracks. Correspondingly rocking the shaft 28 in the opposite direction will force these filler blocks downward and raise the others so that a train may pass without jar over the other rails.

There has thus been provided a simple and efficient device of the kind described and 45 for the purpose specified.

It is obvious that minor changes may be made in the form and construction of this invention without departing from the material principles thereof. It is not therefore 50 desired to confine the invention to the exact form herein shown and described, but it is wished to include all such as properly come within the scope claimed.

Having thus described the invention, what 55 is claimed as new, is:—

1. The combination with a pair of rails intersecting a second pair of rails; of blocks at the points of intersection each having in-

tersecting grooves in its upper surface arranged to accommodate wheel flanges, each 60 of said blocks having a pair of vertically disposed recesses opening upwardly into said grooves at the outer sides of the intersection, filler members slidably vertically in said recesses, and means to raise said filler 65 members selectively to the level of the top of the rails.

2. The combination with a pair of rails intersecting a second pair of rails; of blocks at the points of intersection each having intersecting grooves in its upper surface arranged to accommodate wheel flanges, each 70 of said blocks having a pair of vertically disposed recesses opening upwardly into said grooves at the outer sides of the intersection, filler members slidably vertically in said recesses, and means to raise said filler 75 members selectively to the level of the top of the rails, said means operating simultaneously to depress the other filler member. 80

3. The combination with a pair of rails intersecting a second pair of rails; of blocks at the points of intersection each having intersecting grooves in its upper surface arranged to accommodate wheel flanges, each 85 of said blocks having a pair of vertically disposed recesses opening upwardly into said grooves at the outer sides of the intersection, filler members slidably vertically in said recesses, cam wedges selectively movable 90 under and from beneath said filler members to raise said members selectively, and means to operate said cam wedges.

4. The combination with a pair of rails intersecting a second pair of rails; of blocks 95 at the points of intersection each having intersecting grooves in its upper surface arranged to accommodate wheel flanges, each of said blocks having a pair of vertically disposed recesses opening upwardly into said grooves at the outer sides of the intersection, filler members slidably vertically in said recesses, cam wedges selectively movable under and from beneath said filler members to raise said members selectively, bell 105 crank levers operated by the movement of said cam wedges from beneath the filler members and arranged to engage the respective filler member and force the same downward, and means to operate all of the wedges 110 simultaneously.

In testimony whereof we affix our signatures.

JAMES M. RIHN.
WILLIAM RIHN,
